(57) **CLAIM**

The ornamental design for a trailer lock, as shown and described.

DESCRIPTION

FIG. 1 is a perspective view of a trailer lock, showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of FIG. 1; and,

FIG. 10 is a partial enlarged view of FIG. 2.

The dashed broken lines in the figures are for the purposes of illustrating portions of the trailer lock, which form no part of the claimed design. The dot-dash broken lines in the figures illustrate the periphery of the enlarged view of the trailer lock and form no part of the claimed design.
